UNITED STATES PATENT OFFICE

2,472,874

LADY'S PORTABLE POWDER DISPENSER

Philip Wolfers, Valley Stream, N. Y., assignor to
 Powdermaster Products Inc., New York, N. Y.,
 a corporation of New York

Application November 2, 1944, Serial No. 561,508

2 Claims. (Cl. 132—83)

1

This invention relates to ladies' portable powder dispensers, commonly known and hereinafter referred to as "compacts."

Compacts, in general, include a base, a mirror-carrying cover hinged thereto, a latch diametrically opposite to the hinge for holding the cover closed, and a manually operable element adjacent the latch for releasing the same to permit opening of the cover.

In normal operation, the hinge of a compact is held away from the user in order to position the mirror properly for inspection of the features. This is accomplished by grasping the compact with the thumb at one side of the compact between the hinge and latch, and other fingers of the same hand at the opposite side of the compact. To open the compact, the manually operable latch releasing element is manipulated by the other hand. This use of both hands to open a compact for a long time has been a source of annoyance, since women quite often are encumbered with articles which can be carried for a few moments by one hand but which must be laid down to open a compact with both hands.

In accordance with my present invention, I contemplate the provision of a compact of such improved construction that the same may be held and opened with but one hand, thus enabling the user to inspect herself without laying down all her portable articles. This construction also enables a user to apply makeup more quickly, since the compact can be held and opened with one hand while the other hand holds the makeup article as, for example, a powder puff, or a lipstick, rouge, or mascara applicator.

Another object of the invention is to provide a compact having a novel dispensing means comprising relatively few and simple parts but which, nevertheless, is highly efficient in operation.

A further object of the invention is to provide a compact in which the dispensing means is operated in an improved manner by movement of the same element which releases the latch.

An additional object of the invention is to provide an improved compact which is of durable and inexpensive construction and attractive appearance.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the claims.

In the accompanying drawings, in which is shown one of the various possible embodiments of this invention,

2

Fig. 1 is a top plan view of a compact embodying my invention;

Fig. 2 is an enlarged sectional view thereof taken substantially along the line 2—2 of Fig. 1;

Fig. 3 is a top plan view of the base of the compact before the mounting plate for the powder tray is secured in place;

Fig. 4 is a similar view of said base as it appears before the cover is hinged thereto;

Figs. 5 and 6 are enlarged fragmentary sectional views taken substantially along the lines 5—5 and 6—6, respectively, of Fig. 1;

Fig. 7 is an enlarged sectional view taken substantially along the line 7—7 of Fig. 3; and

Fig. 8 is an enlarged sectional view taken substantially along the line 8—8 of Fig. 4.

Referring now in detail to the drawings, 10 denotes a compact embodying my invention and comprising a base 12 and cover 14.

The compact may be of any desired plan contour adapted to provide a pleasing appearance. However, I prefer for the contour to be such as to furnish lateral holds or grips for the thumb and fingers, the term "lateral" as used herein denoting any point on the plan periphery of the compact which is intermediate the hinge and the latch. To this end, the plan contour of the illustrated compact 10 has two diametrically opposite indentations 16, 18 which are disposed approximately 90° away from the hinge. For aesthetic purposes, four other indentations 20, 22, 24, 26 may also be formed in the plan contour of the compact, these indentations optionally being of the same size and shape as the indentations 16, 18 and being spaced 60° away therefrom, so as to give a pleasing, symmetrical appearance to the compact. It will be understood that indentations 20—26 are provided only to enhance the appearance of the compact and have no bearing upon the operation or handling thereof. It will also be understood that, although I prefer to have the finger holds comprising the indentations 16, 18, 90° away from the hinge and diametrically opposite to each other, such position is not essential and said finger holds may, for example, each be 60° away from the hinge and on opposite sides of the compact, i. e., on opposite sides of the hinge. In addition, the finger holds need not be of the concave configuration illustrated, and may comprise, by way of example, flats in the convex plan curvature of the compact.

It should also be noted that the plan contour of the compact may be controlled by either or both the bottom or cover of the compact. For example, if the cover and bottom are of like size and shape in plan, as is the case in the illustrated embodiment of my invention, then the contour of both will govern the contour of the compact. However, it may be desirable sometimes to have either the bottom or the cover larger than the

other part, in which case the larger part governs the plan contour. In the latter case, it will be appreciated that the contour of the smaller part may vary from the general plan contour of the compact. Thus, if the bottom of the compact has the plan contour illustrated in Fig. 1 and the top is smaller than the bottom, the top may be of circular outline lying wholly within the plan contour of the bottom.

For decorative purposes, I may fashion the outer casing of the compact, including the top and bottom, from a plastic material of any type well known to the art, for example, cellulose acetate, an acrylic resin, or a phenolic condensate. Obviously, if desired, the outer casing could be of metal. As shown, the cover comprises a plastic shell 30, and the base a plastic shell 32. These shells have an external contour which is controlled by the desired appearance of the compact and an inside configuration of such nature as to secure in place the various internal parts of the compact, hereinafter described.

The rear of the bottom shell 32 has a pair of squat pedestals 34, 36 with registered bores 38, 40 therein, the top surface of the pedestals being curved to conform to the desired top contour of the compact. A clear space 41 is provided between the pedestals to receive the bearing portion of the plastic cover shell 30. Said bearing portion includes a pair of parallel circular ears 42 each adapted to lie adjacent a pierced wear plate 43 on an interior surface of the pedestals 34, 36. Said ears, which are integral with the cover shell 30 and extends downwardly from the rear edge thereof, are apertured in registration to rotatably receive a pin 44 which is fixedly secured in the bores 38, 40. The rear portion of the base shell 32 is reinforced by a pair of shoulders 46, 48 underlying the ears 42 and extending upwardly from the base shell partway into the clear space 41. The bearing portion of the cover shell is reinforced by a rib 50 interconnecting the two ears 42 and extending radially inwardly from the hinge toward the center of the compact. A projection 52 at the rear of said rib extends around in back of the pin 44 for a purpose soon to be described.

Means is provided to resiliently bias the cover and base shells rotatably apart to open position. Said means comprises a spring 54 formed from resilient wire into the shape of a helix 56 including a plurality of turns encircling the pin 44 between the ears 42 and having its two ends 58, 60 extending from the helix and shaped to fit against the inside surfaces of the cover and base shells 30, 32. The spring in relaxed position has its two ends 58, 60 in alignment extending on opposite sides of the helix 56, so that said spring biases apart the cover and base in both open and closed condition of the compact.

Means is also provided to check movement of the cover at fully open position approximately 90° away from the base. Such check or stop means may comprise a relatively stiff leaf spring 62 secured to the base shell 32 by imbedded rivets 64 and having a free end 66 lying in the path of travel of the projection 52 on the cover shell 30. Said spring will abruptly but resiliently arrest opening movement of the cover when it is in its proper position.

The cover shell has an interiorly disposed mirror 68 mounted therein in any suitable manner. For example, said shell may have a shallow circular central recess 70 molded therein, the same being interrupted only at the rib 50. The mirror

68 is snugly received in said recess and is held in place by a sheet metal retainer 72 which lies flush against the inner flat surface 74 of the shell 30 surrounding said recess. The outer edge of said retainer is turned in beneath a beveled undercut 76 circumscribing said inner surface 74 to anchor the retainer in the shell, and the inner edge of the retainer is upset and pressed against the beveled side edge of the mirror as at 78.

10 A suitable powder tray 80 is mounted in the base shell 32, resting upon bosses 81. Said powder tray, pursuant to the dispensing feature of the invention later described, is of circular contour and may be centrally disposed in the base shell. The powder tray includes a bottom wall 82 having an upstanding rim 84 and a rolled top edge 86. An outwardly extending flange 88 is integral with the rolled top edge and is disposed below the same. The rolled edge 86 of the tray 15 is pressed through a large central aperture 89 in a mounting plate 90 until the flange 88 abuts against the underside of the plate. Said mounting plate may have a contour substantially similar to that of the base shell 32 but is of slightly small dimensions, and is provided with a depending peripheral rim 92 which is force-fitted within the enclosure defined by the inner surface of a flange 94 running around the periphery of said base shell except at the rear thereof. The depth 20 of insertion of said mounting plate 90 is defined by abutment of the lower edge of the rim 92 against a plurality of nibs 96 provided at spaced points around the inner surface of the flange 94.

25 A powder puff tray 98 is also provided, said tray comprising a base wall 100 with an upstanding rim 102 adapted to be frictionally fitted against the inner surface of the rim 84 of the powder tray. This friction fit is tight enough to hold the powder puff tray in place and prevent powder from leaking 30 out from between the powder tray and powder puff tray but is not so tight that the tray cannot be dislodged manually. The depth of insertion of the powder puff tray is limited by a rolled bead 104 from which there extends an upwardly tilted 35 annular flange 106 beneath which a finger nail 40 may be inserted when it is desired to pry loose the powder puff tray.

45 A powder puff 108 is adapted to be captively received, at such time as the compact is closed, between said powder puff tray 98 and the mirror 68.

50 Pursuant to my invention, I provide a dispensing means of simple construction which is positive and noiseless in operation. Such means comprises a distributor 110 in the form of a circular sheet metal disc 112 having a depressed hub 114 from which a plurality of angularly spaced arms 116 integrally extend. As will be seen later, the distributor is rotated in a predetermined direction (counterclockwise as viewed in Fig. 4). The leading edge 118 of each arm is provided with a 55 forwardly and downwardly sloping surface 120 (Fig. 8) and is adapted to slide on the upper surface of the bottom wall 82 of the powder tray, so that as said distributor is turned in the aforesaid direction, it will raise powder from said tray and force the same toward the top of the distributor. The distributor is so dimensioned that its top surface slidably engages the undersurface of the bottom wall 100 of the powder puff tray 98. Said bottom wall has a plurality of radial slits (or 60 round holes) 122 formed therein in a suitable manner as, for example, by cutting. Preferably, these slits are so narrow and are inclined at such an angle, with regard to the thickness of the bottom wall 100 of the powder puff tray, that the 65

upper overhanging edge 124 of each slit projects over the lower edge 126 of the opposite wall of the slit. Powder raised up from the powder tray compartment is forced through said slits upon rotation of the distributor, the amount of powder urged through a slit each time an arm 116 passes there-beneath being relatively small, due to the small size of the slit.

In accordance with my invention the distributor is rotated through a sufficient angle each time the same is actuated to provide a substantial amount of powder on the upper surface of the bottom wall of the powder puff tray. Also, enough slits 122 are formed in said powder puff tray to allow a considerable total amount of powder to be provided thereon upon each operation of the distributor. This amount of powder will be determined by the requirements of the trade and should in each instance be at least equal to the minimum amount of powder likely to be needed by a user. If additional powder is desired, the distributor may be actuated more than once, as will later be seen. In the instant case I have shown six slits 122 in the powder puff tray, with each slit approximately $\frac{1}{8}$ of an inch wide and inclined at an angle of about 45° to the horizontal. It will be understood, however, that these dimensions and numbers are given only by way of example and are in no way to be construed as limitative.

As indicated above, means is provided to rotate the distributor in a counter-clockwise direction. Said means comprises a vertical shaft 128 having a journal portion 130 rotatably mounted in a central aperture 132 in a base plate 184. Said base plate is press-fitted into a recess 136 in the base shell 32. The shaft 128 is also journaled in a central aperture 138 in the powder tray 60 and a central aperture 140 in the powder puff tray 98. The shaft 128 and distributor 110 are suitably interconnected so that when the shaft is turned in a counter-clockwise direction in a manner later described, the distributor will turn with it. Since in the preferred form of my invention, herein illustrated, I have shown an oscillatory motion imparted to the shaft 128, said shaft and the distributor desirably are interconnected by a one-way drive which functions to prevent retrograde movement of the distributor during return (clockwise) travel of the shaft 128.

Any conventional one-way drive may be employed. Preferably, however, the one-way drive provided is of the noiseless type, both to minimize wear and to conceal the presence of the mechanism. A one-way drive which I have found to be satisfactory is best shown in Figs. 2 and 4 and comprises a disc 142 press-fitted on the shaft 128. Said disc is adapted to freely turn within the depressed hub 114 of the distributor. The disc has a plurality of wedge-shaped peripheral notches 143 cut therein, each notch being adapted to receive a ball 144 of such size that the ball will turn freely in the larger end of the notch but will wedge between the narrow end of the notch and the side of the hub 114. A spring 146 biases each ball toward the narrow end of the notch. The balls are retained in place by a washer 148 mounted on the shaft 128 between the powder puff tray and disc 142, said washer being held in place by splays 150 immediately above the washer. The shaft 128 freely passes through an aperture 152 in the center of the hub 114.

When the shaft 128 is turned in a counter-clockwise direction, the balls 144 will wedge between the disc 142 and hub 114 to drive the dis-

tributor in a like direction. When the shaft 128 is turned in a clockwise direction, the balls 144 are urged toward the larger end of the wedge-shaped grooves and allow the disc 142 to turn freely in said hub without rotating the distributor.

The means for oscillating the shaft 128 includes a narrow drum 154 press-fitted on the shaft 128 and having a wire cable 156 wrapped around the periphery thereof a sufficient number of degrees, at least about 450°, to insure binding of the cable on the pulley, so that when the cable is shifted it will turn the pulley. The ends of the cable are attached to the two arms 158, 160 of a bell crank lever 162. Said lever is formed from sheet metal and has a portion 164, intermediate the points where the cable ends are connected, which is resilient about an axis parallel to the shaft 128 whereby the two arms of the bell crank lever may be sprung together while the cable ends are being attached to maintain said cable under tension and to insure binding thereof about the drum. The bell crank lever is pivotally mounted on a pin 166 secured to the base shell 32. Said lever is rotatably biased in a clockwise direction (as viewed from Fig. 3) by a cantilever leaf spring 168 which presses against the lever arm 158 and is anchored on a post 169 projecting from the base plate 184.

The bell crank lever is oscillated, in order to dispense powder through the bottom of the powder puff tray, by a manually operable element in the form of a button 170 which, in accordance with my invention, is mounted laterally of the plan contour of the compact and preferably at or adjacent one of the finger holds, as, for example, the indentation 18. Said button is slidably received between two guides 172, 174 forming part of the peripheral flange 96 of the bottom shell 32. The mounting plate 90 slidably engages the upper surface of the button (Fig. 5) to prevent the same from jumping up and a depending rib 176 is slidably received in a groove 178 in the bottom shell 32 to limit forward and retarding movement of the button. The button engages a high spot 179 on the bell crank lever 162. Normally, the button is maintained in extended position, as shown in Figs. 3 and 4, by the spring 168. When the button is pushed radially inwardly, it causes the bell crank lever 162 to turn in a counter-clockwise direction, as viewed from Fig. 3. This will turn the disc 142 in like direction and rotate the distributor arms 116 in such manner as to raise powder.

It will be appreciated that the foregoing movement of the button 170 may be accomplished by pressing against the compact the fingers of the same hand that is holding the compact with the mirror 68 facing the user.

It will also be seen that the dispensing action may be readily repeated.

The cover and bottom of the compact are detachably secured together at a point diametrically opposite to the hinge by a latch which comprises a stud 180 whose base 181 is imbedded in the cover shell 30. Said stud has an enlarged tapered head 182 against whose back surface an extension 184 of the bell crank lever arm 160 is adapted to lie when the compact is closed. This engagement between the head of the stud and the extension 184 takes place beneath the surface of the mounting plate 90 (Fig. 2), said stud passing through an aperture 186 in said plate.

The latch is released when the button 170 is pressed radially inwardly and the latch is engaged by pressing the cover down towards the

base. This latter action forces the tapered surface of the stud head 182 against the extension 184 camming said extension out of the path of travel of the stud head, until the stud head passes the extension, whereupon said extension springs back into locking engagement with the back stud head. Due to the foregoing construction, although the latch is diametrically opposite to the hinge, I am able to easily release the same by manipulation of an element which is disposed laterally of the compact and in this manner render the compact capable of being opened with the same hand which is holding the compact in proper position for use subsequent to opening.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A powder compact comprising an approximately round base, a cover, a hinge to connect the cover to said base, said hinge being disposed adjacent the periphery of the base and having its axis of rotation perpendicular to a line running from the center of the base to the hinge, a spring connected to the cover and base to resiliently urge said cover to open position, a mirror mounted interiorly of said cover, whereby when said compact with its cover open lies in a user's palm and is grasped by the fingers at the periphery of the base on both sides of the hinge and approximately half way between the hinge and the diametrically opposite part of the compact at points about 90° away from the hinge with the center of the base

as a reference point, the mirror will be positioned for inspection of the user's features, said base having opposed peripheral indentations approximately half way between the hinge and the diametrically opposite part of the compact at points about 90° away from the hinge with the center of the base as a reference point, said indentations serving as finger holds, a powder tray in said base, a latch for detachably securing said cover to said base at a point approximately diametrically opposite to the hinge, and a manually operable element disposed in one of said indentations for releasing the latch, said latch-releasing-element being shiftable radially with respect to the center of said base, whereby said latch may be released by pressing against the base of the compact and the latch-releasing-element, the fingers of the hand holding the compact in proper position for use subsequent to opening.

2. A compact as set forth in claim 1 wherein the powder tray is provided with a perforate top and wherein means is provided to transport powder in limited predetermined quantities through said top, said means being operable by the latch-releasing-element.

PHILIP WOLFERS.
